Primary Examiner — Mark Goodwin(74) *Attorney, Agent, or Firm* — Muetting, Raasch & Gebhardt, P.A.(57) **CLAIM**

The ornamental design for a lawn mower power head, as shown and described.

DESCRIPTION

FIG. 1 is a right rear perspective view of a lawn mower power head incorporating the new design;

FIG. 2 is a left front perspective view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a top plan view thereof.

The features shown in broken lines in the figures, including the mower handle, handle controls, and handle-mounted brackets, are for illustrative purposes only and form no part of the claimed design.
